(57) **CLAIM**

The ornamental design for a fishing lure, as shown and described.

DESCRIPTION

FIG. 1 is a perspective view of a fishing lure showing the new design;

FIG. 2 is a left side elevational view thereof, of which the right side is a mirror image;

FIG. 3 is a front elevational view thereof;

FIG. 4 is a rear elevational view thereof;

FIG. 5 is a bottom plan view thereof; and

FIG. 6 is a top plan view thereof.

FIG. 7 is a perspective view of a fishing lure showing a second embodiment of the new design;

FIG. 8 is a left side elevational view of the second embodiment thereof, of which the right side is a mirror image;

FIG. 9 is a front elevational view of the second embodiment thereof;

FIG. 10 is a rear elevational view of the second embodiment thereof;

FIG. 11 is a top plan view of the second embodiment thereof; and

FIG. 12 is a bottom plan view of the second embodiment thereof; and,

FIG. 13 is a cross-sectional view of a fishing lure showing the new design.
